ROOM DIVIDER LAMP CONSTRUCTION

Nathan Meyerowitz, Chicago, Ill., assignor to D & W Manufacturing Company, Inc., Chicago, Ill., a corporation of Illinois

Filed Jan. 18, 1960, Ser. No. 3,014

4 Claims. (Cl. 240—81)

My invention relates to improvements in room divider lamp construction.

My invention relates more particularly to refinements in the same by the use of which better construction, easier assembly and easier use of the same may be obtained.

Room divider pole lamps of the type to which I refer are usually provided with a three-section pole and a pair of spring mounted foot members for positioning the same between the ceiling and the floor of a room in which they are used. With the usual type of room divider pole lamp now in use there is very little bearing surface for the rods of the foot portions, with the result that very frequently the room divider itself will be canted in position and thus look unbecoming. The short bearing for the foot rod which is usually only the thickness of the metal at the hole through the pole caps thus permits of possible bending or canting and results in an untidy appearance in use.

The principal object of the present invention is to provide an improved construction of room divider lamp or pole lamp.

A further object of the invention is to provide such a construction which will result in an improved appearance and in more workmanlike action.

A further object of the invention is to provide a pole lamp having suitable bearing members at both ends of the same.

A further object is to provide an improved room divider or pole lamp which permits the wiring of the same without threading the wire through openings in the pole cap at either end.

Another object of the invention is to provide an improved pole cap for use in room divider lamp construction.

Other objects and advantages will be more apparent from the following description wherein reference is had to the accompanying drawings, upon which:

Fig. 1 is a side elevational view showing a room divider lamp in position between the floor and the ceiling of a room;

Fig. 2 is a full size fragmentary vertical sectional view with the portion between the two ends of the lamp post foreshortened;

Fig. 3 is a cross-sectional view therethrough, taken on the line 3—3 of Fig. 2;

Fig. 4 is a fragmentary side perspective view of a portion of the lamp post and foot supporting rod; and

Fig. 5 is a bottom plan view taken generally on the line 5—5 of Fig. 4.

In the embodiment of the invention which I have chosen to illustrate and describe the same, the usual type of room divider lamp is shown and may include the tubular post member 10 which is usually made of three sections, the upper and lower sections 12 and 14 having the end 16 telescopically received in the center section 20. The adjustable lamps 22 are also mounted in the center post 20 and have the extension wire 24 connected thereto, the

2

extension wire being passed through a rubber grommet that is mounted in an elongated slot 28 at the lower end of the tubular portion 14. The electric cord is provided with the usual push-in plug 30.

As previously stated, the usual room divider lamp is provided with a pair of foot members which include the foot rod 32 and the pad 34 that bears against the ceiling C and the floor F to support the lamp in position. The rods 32 normally pass through end caps at the upper and lower ends of the pole sections 12 and 14. In the construction shown, I provide a top pole cap 40 which is mounted by means of a bayonet slot connection in the upper end of the tubular member 12.

The bayonet slot connection may include the pins 42 fastened in the tube 12 adjacent its open end, the pins riding in suitable bayonet slot grooves 44 in the surface of the body 46 of the cap 40 in the usual manner.

In order to provide a smoother and more easily operable construction and one which is sturdier in use, I have provided an elongated sleeve portion 48 as part of the cap 40, the sleeve portion 48 forming an elongated bearing for the rod 32. The rod 32 and pad 44 are usually pressed upwardly in the tube 12 by means of a coiled spring member 50 below the lower plate 52 attached to the rod 32, thus permitting vertical adjustment for ceilings of various heights. The lower cap member 60 may also be mounted in the end of the tube by means of a bayonet slot connection as described, the cap 60 also having an elongated sleeve portion 62 which forms a sliding bearing for the bottom foot rod 32.

The bottom foot rod 32, which may be approximately 18 inches long, is not spring pressed as is the upper foot rod, but rather it is held in place by a thumb screw 64 which engages the post, being mounted in a tapped hole 66 in a boss 68 at the lower end of the cap 60. This boss may preferably have the flattened sides 70 as shown, so that it may easily be grasped with a pliers or wrench to engage or disengage the bayonet slot from the pins 42.

The bottom cap 68, as best shown in Figs. 2 and 3, provides a space for the cord 24 to the elongated slot 28 in the lower end of the tubular member 14, being cut off to form a sector-shaped opening 80 by means of the side walls 82 and 84 of the body portion 46.

With the above and foregoing construction, it is an easy matter, when the room divider lamp is received in a home in a disassembled manner, to connect the cord 24 from the lamp post 20 to the elongated slot 28 through the tubular member 14, placing the grommet 26 that is on the cord up into the slotted opening 28, so that both the cord and the grommet are held in fixed position. The lower cap member 60 may now be easily fastened in place without disturbing the cord 24 by reason of the sector-shaped cavity 80 provided in the cap.

By making the lamp divider with a spring-pressed foot 32 and an adjustable foot 32 at the bottom, the room divider lamp can be positioned equally between the floor and the ceiling and fastened by means of the set screw 64, thus enhancing the appearance of the room divider lamp and providing a better fixture between the top and bottom supports for the same.

While I have illustrated and described a specific embodiment of the invention, it will be apparent to those skilled in the art that changes and modifications may be made in the exact details shown and I do not wish to be limited in any particular; rather what I desire to secure and protect by Letters Patent of the United States is:

1. The combination with a room divider lamp of the type having an elongated tubular housing, electric lights and reflectors connected to said housing at several points throughout its length and a pair of foot rods, one extending from each end of said housing, of a cap at each end

of said housing, each of said caps having a segmental shoulder extending into said housing and connected to said housing by a bayonet slot connection, an elongated bearing hub formed integral with each cap and extending axially therethrough, each of said hubs having an axial bore therein, said foot rods extending through said bores, the segmental shoulders on said caps each having a circular transverse flange bearing against the end of said housing, a plurality of radial walls thereon between said hub and said shoulder, two of said walls diagonal to each other and forming the ends of said shoulder and defining a sector-shaped space between said housing and said hub, said housing having a longitudinal slot extending from its end, a rubber grommet engaged in said slot, an electrical conduit extending therethrough, said conduit entering said housing adjacent said shoulder and in the sector-shaped space formed thereby and extending to said lights.

2. The combination with a room divider lamp of the type having an elongated tubular housing, electric lights and reflectors connected to said housing at several points throughout its length and a pair of foot rods, one extending from each end of said housing, of a cap at each end of said housing, each of said caps having a segmental shoulder extending into said housing and connected to said housing by a bayonet slot connection, an elongated bearing hub formed integral with each cap and extending axially therethrough, each of said hubs having an axial bore therein, said foot rods extending through said bores, the segmental shoulders on said caps each having a circular transverse flange bearing against the end of said housing, a plurality of radial walls thereon between said hub and said shoulder, two of said walls diagonal to each other and forming the ends of said shoulder and defining a sector-shaped space between said housing and said hub, said housing having a longitudinal slot extending from its end, a rubber grommet engaged in said slot, an electrical conduit extending therethrough, said conduit entering said

housing adjacent said shoulder and in the sector-shaped space formed thereby and extending to said lights, one of said caps having a boss below said lateral flange and a thumb-screw therein for engagement with a foot rod.

5 3. A room divider lamp pole cap for fitting into the upper and lower ends of a tubular lamp pole, said cap having a shell portion extending approximately two-thirds of the circumference of the bore of the lamp pole, a lateral circular flange at one end of said shell portion, an axial elongated tubular ring portion extending upwardly from said flange, said shell portion concentric to said ring portion and having three equally spaced radial ribs connecting the same, two of said ribs forming the ends of said shell portion and defining a space adjacent said ring portion and above said flange for passage of an electric cord.

10 4. A room divider lamp pole cap for fitting into the upper and lower ends of a tubular lamp pole, said cap having a shell portion extending approximately two-thirds of the circumference of the bore of the lamp pole, a lateral circular flange at one end of said shell portion, an axial elongated tubular ring portion extending upwardly from said flange, said shell portion concentric to said ring portion and having three equally spaced radial ribs connecting the same, two of said ribs forming the ends of said shell portion and defining a sector-shaped space adjacent said ring portion and above said flange for passage of an electric cord into said lamp pole, said lateral flange having a boss therebelow and a thumb screw mounted in said boss.
